(57) **CLAIM**

The ornamental design for a solar cell module, as shown and described.

DESCRIPTION

1. Solar cell module

1.1 : Perspective

1.2 : Front

1.3 : Back

1.4 : Top

1.5 : Bottom

1.6 : Right

1.7 : Left

1.8 : Partial enlarged view of front view

1.9 : Enlarged top view

1.10 : Cross-sectional view taken on line 1.10-1.10 of FIG. 1.8

In the reproductions, the broken lines are for the purpose of illustrating environment only and form no part of the claimed design. The parallel thin lines in the reproductions represent contours only and do not illustrate an ornamentation or decoration on the surface of the product.
